DISPENSING DEVICE

Charles W. Ward, Los Angeles, Calif.

Application December 8, 1939, Serial No. 308,199

5 Claims. (Cl. 221—60)

This invention relates to dispensing devices.

The invention has for an object the provision of a device adapted to be secured to the threaded neck of a tube, such as the neck of a collapsible tube holding tooth paste, shaving cream, or other substance, adapted to be exuded through the neck when the tube is rolled or otherwise compressed, said dispensing device taking the place of the ordinary cap received on the threaded neck and adapted to allow the opening of the neck to be positioned so that material may be exuded therethrough or, upon releasing the tube, to permit the tube to have the neck thereof automatically closed.

15 The present device contemplates the use of a bracket adapted to be secured to some object, and a pair of arms pivoted to said bracket, one of which arms is threaded for engagement with the threads of the neck of a collapsible tube, and 20 the other of which arms cooperates with the end of the neck to close the opening in the same, the relationship being such that when the tube is manually moved, the tube carrying arm will move with said tube away from the closure arm and 25 when the tube is allowed to drop under gravity, the closure arm is positioned directly over the orifice or outlet opening of the neck. This construction accomplishes an object of the invention 30 of providing a dispensing device which positively closes the opening in the neck regardless of the quantity of material exuded from the tube.

One difficulty with devices now known to the 35 inventor which are adapted to take the place of the usual cap on tubes is due to the expense of constructing such a device. The present invention is very cheap to manufacture in that it costs but a few cents and can, therefore, be readily placed in a box by the manufacturer or seller 40 of dental or shaving creams without greatly adding to the normal expense of the cream.

In the drawing:

Figure 1 is a side elevation of the device, a 45 certain portion being shown in section to illustrate connection of the device with the threaded neck of a collapsible tube.

Figure 2 is a front elevation of the device associated with a collapsible tube,

50 Figure 3 is a fragmentary side elevation of the device, the tube being raised so that the content thereof may be exuded through the neck upon compressing the tube, and,

55 Figure 4 is a sectional view on the line 4—4 of Figure 1.

Referring now with particularity to the drawing, 1 indicates the improved dispensing device as an entirety, and 2 a collapsible tube of the type employed for dental and shaving creams, and wherein 3 is a threaded neck of said tube. 5

The device 1 includes a bracket 4 which may have two offset parallel portions 5 and 6 with an integrally formed connecting piece 7, the portion 5 having through bores whereby screws may be passed therethrough and received in some supporting member 8, thereby holding the bracket in substantially a vertical position. The portion 6 of said bracket is provided with a transverse bore 9 and the end of said portion provided with a shoulder 10. A pair of arms 11 and 12 are 15 swingingly secured on opposite sides of the portion 6 of the bracket through the medium of a stud or pin 13. The arm 11 is given a structural twist at 14 and provided with a threaded bore 15 adapted to receive the threaded neck 3 of the 20 tube 2. The arm 11 is termed the tube carrying member. The arm 12 is given a structural twist at 16 and formed with a concavo-convex protuberance 17 which when the arms are cooperating, is in alignment with the threaded opening 25 15. A coil spring 18 has one end thereof passed through an opening in the part 6 of the bracket, shown at 19 in Figure 2, and the opposite end of said spring is passed through an opening in the arm 12, as shown at 20. This coil spring at all 30 times urges the arm to swing in a clockwise direction relative to the bracket, rotation being limited by the arm engaging the shoulder 10, see Figure 3.

The operation, uses and advantages of the invention just described are as follows:

The bracket is mounted so as to be in a vertical position relative to the supporting member 8, as shown in Figures 1 to 3, inclusive. The cap that is usually supplied with collapsible tubes is 40 removed, and the neck threaded into the threaded opening 15 of the arm 11. This operation is conveniently accomplished by swinging the arm 11 to the position shown in Figure 3. Upon dropping the tube, the same will fall under gravity and a portion of the neck of the tube which projects beyond the surface 21 will be received within the confines of the member 17 as, for instance, illustrated in Figures 1 and 4. When the neck is received as aforesaid, the arm 12 will be 45 moved from engagement with the shoulder 10, see Figure 1. It will be remembered that the arm 12 is spring actuated so that the portion 17 is at all times urged to cover the outlet of the neck of the tube.

When it is desired to dispense any of the material from the tube, the tube may be swung, together with the arm 11, about the pivot point of said arm to the position shown in Figure 3, whereupon pressure upon the tube will cause the contents to be exuded therefrom, as indicated by the dotted lines at 22. When the tube is dropped, any extra material at the outlet end of the neck of the tube will not be removed therefrom by the member 17 unless, of course, considerable of the material from said tube was left projecting from the opening in the neck. It is expected that the user of the device will, under ordinary circumstances, wipe the tube clean with a brush or other article so that paste will not build up within the member 17. However, it is evident that even if the material does build up within the member 17 that the construction of the device is such that direct air contact with 20 said material is prevented so that the material will not dry and become hard.

I claim:

1. In a device of the character disclosed, a bracket adapted to be vertically secured to a supporting structure, a pin carried by one end of said bracket, a pair of arms positioned on opposite sides of said bracket and swingingly mounted on said pin, one of said arms formed with a threaded bore for threaded engagement with the neck of a collapsible tube and the other of said arms provided with a concavo-convex cap, and means normally urging said last named arm to position said cap over the threaded opening of the other arm.
2. In a device of the character disclosed, a bracket adapted to be secured to a supporting structure, an arm swingingly mounted at one end of said bracket, said arm formed with a threaded bore to receive the threaded neck of a collapsible tube and said arm normally being swung from a vertical position under influence of gravity when a collapsible tube is secured thereto; a second arm swingingly mounted to said bracket,

said second arm formed with a concavo-convex cap, and resilient means urging said arm and its cap to overlie the opening of the first arm and the neck of any tube secured thereto.

3. In a device of the character disclosed, a bracket adapted to be secured to a supporting structure, an arm swingingly mounted at one end of said bracket, said arm formed with a threaded bore to receive the threaded neck of a collapsible tube and said arm normally being swung from a vertical position under influence of gravity when a collapsible tube is secured thereto; a second arm swingingly mounted to said bracket, said second arm formed with a concavo-convex cap, resilient means urging said arm and its cap to overlie the opening of the first arm and the neck of any tube secured thereto, and stop means for said bracket for limiting movement of the resiliently urged arm in one direction. 20

4. A device of the character disclosed, including a bracket adapted to be vertically secured to a support, a pin carried by said bracket, a pair of arms swingingly mounted on said pin, one of said arms being formed with a threaded bore 25 into which the threaded neck of a collapsible tube is screw seated, said other arm being formed with a cap to receive the projecting end of the neck of said collapsible tube when said first arm is swung against said second arm, under the influence of the weight of said collapsible tube, and a spring coiled around said pin with one end of said spring connected to said bracket and the other end of said spring connected to said second arm for urging said second arm toward said first arm to position said cap over the projecting end portion of said neck of said collapsible tube. 30

5. A device as claimed in claim 4 including a stop on said bracket to be engaged by said second arm to limit the movement of said arm under the influence of said spring. 35 40

CHARLES W. WARD.
